UNITED STATES PATENT OFFICE.

ALEXANDER GLASS, OF WHEELING, WEST VIRGINIA.

HEATING-FURNACE.

1,074,258.

Specification of Letters Patent. Patented Sept. 30, 1913.

Application filed February 8, 1912. Serial No. 676,468.

To all whom it may concern:

Be it known that I, ALEXANDER GLASS, residing at Wheeling, in the county of Ohio and State of West Virginia, a citizen of the 5 United States, have invented or discovered certain new and useful Improvements in Heating-Furnaces, of which improvements the following is a specification.

In the manufacture of sheets, the bars are 10 heated in what is known as the "pair furnace" and any subsequent heating required while reducing the bars to sheets, is effected in the "sheet furnace." Originally these furnaces were entirely independent, but generally under the present practice, the heating chambers for the pairs and sheets are formed in one structure and both heated from a common source or fire chamber, the heating chambers being arranged in such relation to each other and so connected, that the heat and products of combustion reach the sheet heating chamber, after passing through the "pair chamber." The maintenance of the proper temperature in the sheet 25 heating chamber, is a matter of primary importance and such temperature must be had regardless of the temperature best adapted for the heating of the bars.

The invention described herein relates to 30 certain improvements whereby both chambers although heated from a common source or fire chamber, may be maintained at temperature best suited for their respective purpose.

35 The invention is hereinafter more fully described and claimed.

In the accompanying drawings forming a part of this specification Figure 1 is a longitudinal sectional elevation of my improved furnace; figs. 2, 3 and 4 are transverse sections in planes indicated respectively by the lines II--II, III--III and IV--IV, fig. 1.

In the practice of my invention, the furnace is provided with a combustion chamber 1 in which solid or fluid fuel may be employed, a chamber 2 for heating the bars and a chamber 3 for heating the sheets. The pair chamber is arranged transversely of the furnace and adjacent to the combustion chamber, the rear or bridge wall of the latter forming a side wall of the pair chamber. The opposite wall of the pair chamber forms the rear wall of the sheet chamber 3, the charging opening 4 of the latter being arranged in the front wall of the furnace. The pair chamber is provided with a top 5

preferably arched transversely of the furnace as shown in Fig. 3. The furnace is so constructed that a flue or passage 7 is provided extending along, but not through the pair chamber so that heat, products of combustion, etc., may pass directly from the combustion chamber into the sheet chamber. This flue or passage is preferably formed intermediate the top 6 of the furnace and the top of the pair chamber. As will be readily understood by those skilled in the art, the pair chamber will be heated to some extent by radiation from the side walls and top, all of which are subjected to a high heat, but the principal source of heat is from the flue 7 through one or more openings 8 in the top 5 of the pair chamber. While it is believed that one opening of sufficient size will insure an ample flow of products of combustion, etc., to maintain the desired heat in the pair chamber, it is preferred to form two openings in the top 5 adjacent to the front and rear side walls thereby to insure a circulation through the chamber. It is preferred that the opening or openings 8 be made somewhat larger than is theoretically necessary for a proper heating of the chamber 2, and to provide movable tiles 9, which rest on the tops 5 and can be shifted to vary the area of the opening 8. Any suitable means may be employed for shifting the dampers or tiles 9, but as their positions will not be changed very often, a rod introduced through side openings 10 in the flue wall will be generally sufficient.

The stack 11 is connected with the front portion of the sheet chamber by a flue 12, and in order to prevent excessive heating of the rear end of the sheet chamber, the lower wall of the flue 7 is extended as at 13 beyond the rear wall of the sheet chamber.

While the improvement is applied to a double furnace i. e. two pair chambers and two sheet chambers, supplied from a common combustion chamber, it will be readily understood that the improvements can be embodied equally well in a single furnace having one pair and one sheet heating chamber.

I claim herein as my invention:

1. A furnace having in combination, a combustion chamber, two heating chambers, a flue or passage extending from the combustion chamber over the top of one of the heating chambers to the other chamber, an opening connecting the first chamber to said

flue or passage, and means for varying the area of said opening.

2. A furnace having in combination, a combustion chamber, two heating chambers, a flue or passage extending from the combustion chamber to one of said heating chambers, a plurality of openings from said flue or passage to the other heating cham-

ber and means for varying the areas of said openings.

In testimony whereof I have hereunto set my hand.

ALEXANDER GLASS.
